[57] CLAIM

The ornamental design for a display rack, substantially as shown and described.

DESCRIPTION

FIG. 1 is a perspective view of a display rack showing my new design;

FIG. 2 is a front elevational view of FIG. 1;

FIG. 3 is a reduced rear elevational view of FIG. 1; FIG. 4 is a side elevational view taken from the left of FIG. 1;

FIG. 5 is a top plan view of FIG. 1;

FIG. 6 is a bottom plan view of FIG. 1;

FIG. 7 is a perspective view of a second embodiment of the design of FIG. 1, the only difference being the inclusion of three additional partitions in the bottom row.

FIG. 4

FIG. 5

FIG. 2

FIG. 3

FIG. 6

FIG. 7
